UNITED STATES PATENT OFFICE

CHARLES F. KETTERING, OF DAYTON, OHIO, ASSIGNOR TO GENERAL MOTORS RESEARCH CORPORATION, OF DETROIT, MICHIGAN, A CORPORATION OF DELAWARE

HYDRAULIC SLACK ADJUSTER

Application filed May 21, 1927. Serial No. 193,253.

This invention relates to engines of the type in which the crankshaft is replaced by a cam provided with two or more lobes and the connecting rods have anti-friction rollers at their lower ends engaging the cams. In the case of four-cycle internal combustion engines, this construction possesses the advantage that one or more power strokes of each piston may be obtained during a single revolution of the cam shaft. One of the problems of design presented by this kind of engine is that of maintaining the connecting rod rollers in engagement with the cam at all times. Owing to the inertia of the parts, their con-

traction and expansion as a result of temperature changes, and the use of springs having natural periods of vibration near the driving range, it is practically impossible with a purely mechanical gear to avoid considerable lash. When lash exists, the action of the engine will be unsatisfactory, particularly at high speeds, because of irregularity in the movement of the piston. The engine will also be noisy because of the impact of the rollers on the cams.

As a solution of this problem, I propose to employ hydraulic mechanism for maintaining the connecting rods at all times in engagement with the cams. This mechanism may take the form of an hydraulic chamber so located as to resist the movement of the rollers away from the cam shaft. The chamber may be provided with a relatively movable wall continuously urged outwardly by a spring and may be connected with a supply of lubricant, the connection being equipped with a valve so that in the event of leakage of oil from the chamber or the contraction of the parts of the engine as a result of cooling, additional oil will be drawn into the chamber to take up the lash which would otherwise develop.

In the drawing, the figure is a sectional view thru a portion of a cam type engine showing my invention applied thereto.

2 indicates a portion of the crankcase of an engine having cylinders 4 radially arranged. Pistons 6 provided with connecting rods 8 reciprocate in the cylinders and the lower ends of the connecting rods are provided with

rollers 10 engaging a two-lobed cam 12 mounted on the engine shaft 14. To the rollers are pivoted arms 16 and 18 respectively, these arms having a common fixed pivot at 20. To the upper end of the arm 16 is connected by link 22 a piston 24 reciprocating in cylinder 26 formed in or secured to the upper end of the arm 18. Within the cylinder 26 is arranged a coil spring 28 which tends to separate the piston and cylinder and to thereby cause the arms 16 and 18 to swing in opposite directions so as to urge the corresponding rollers 10 into engagement with the cam 12.

The construction, as so far described, would operate more or less satisfactory as a mechanical means for maintaining the rollers in engagement with the cam. However, I find it more satisfactory to convert the cylinder 26 into an hydraulic chamber so that movement of the rollers away from the cam is prevented by the body of oil in the chamber. This may be done in a number of ways, but I have illustrated conduit 30 leading from a suitable oil reservoir, such as the crankcase, passing centrally thru the pivot 20 and then connecting with the cylinder 26. The purpose of passing the conduit 30 through the pivot 20 is to permit the use of rigid conduit rather than flexible conduit for supplying oil to the hydraulic chamber 26. A non-return valve 32 may be provided at the point of connection with the cylinder. The oil in conduit 30 may be under the pressure supplied by the usual engine oil pump.

The operation of the engine is as follows:

Upon rotation of the shaft 14, the pistons with their connecting rods will be reciprocated back and forth in the cylinders, each piston completing a cycle of movement in one revolution of the shaft so that there is one power impulse per piston during each revolution. As previously described, the spring 26 urges the arms 16 and 18 in a direction to cause the rollers 10 to at all times engage the periphery of the cam. Movement of the rollers away from the cam is resisted by the body of oil contained in the cylinder 26. In certain positions of the cam, both rollers will be forced outwardly and the

resulting contraction of the hydraulic chamber will cause the oil to be forced outwardly between the cylinder 26 and piston 24. A similar action will take place upon the expansion of the parts of the gear as a result of warming up of the engine. Upon expansion of the hydraulic chamber at other points in the cycle, or as a result of the contraction of the parts, oil will be drawn into the chamber 26 thru the conduit 30 past the valve 32 so that it is thus insured that the chamber is at all times filled with liquid.

I claim:

1. In combination a revolute cam, a pair of reciprocating members having parts engaging said cam, arms pivoted to said members and an hydraulic chamber interposed between said arms so as to resist separation of the members from the cam.

2. In the combination as defined in claim 1, said arms having a common pivot and said hydraulic chamber being interposed between portions of said arms lying on the opposite side of said pivot from the points of engagement with said cam.

3. In the combination as defined in claim 1, and means for replenishing the supply of oil in said chamber.

4. An engine having a revolute cam, cylinders, pistons in the cylinders, connecting rods connected to the pistons at one end and bearing on the cam at the other end, arms pivoted to said rods and an hydraulic chamber interposed between said arms for resisting movement of the arms away from the cams.

5. An engine having a revolute cam, cylinders, pistons in the cylinders, connecting rods connected to the pistons at one end and bearing on the cam at the other end, arms centrally pivoted on a common pivot, one end of each arm being pivoted to one of said connecting rods and an hydraulic chamber interposed between the other ends of the arms for resisting separation of the connecting rods from the cam.

6. In the combination as defined in claim 5, said chamber being in the form of a cylinder connected to one of the arms, a piston in the cylinder connected to the other arm, and means for admitting oil to the cylinder to replenish the supply.

7. An internal combustion engine comprising a cam, cylinders, pistons in the cylinders, connecting rods pivoted to the pistons at one end and provided with rollers at the other end engaging the cam, arms pivoted to the rods, said arms having a substantially central common pivot and spring means interposed between the opposite ends of the arms for urging the rollers in a direction to engage the cam.

8. An internal combustion engine comprising a cam, cylinders, pistons in the cylinders, connecting rods pivoted to the pis-

tons at one end and provided with rollers at the other end engaging the cam, arms pivoted to the rods, said arms having a substantially central common pivot, and spring means interposed between the opposite ends of the arms for urging the rollers in a direction to engage the cam, one of said last-named ends being provided with a cylinder, a piston in the cylinder connected to the other of said last-named ends, said spring means tending to separate said piston and cylinder.

9. In an engine, a revolute cam, cylinders, pistons in the cylinders having connecting rods provided with rollers engaging the cam, levers pivoted to said rods and to each other, and means common to the levers for yieldingly urging them against the cam.

10. An engine comprising a cam, cylinders, pistons in the cylinders, said pistons being provided with parts adapted to follow the cam, arms each pivotally connected at one end to one of the pistons, said arms being pivoted to each other, and yielding means engaging the arms at points remote from said ends for causing the parts to yieldingly follow the cam.

11. An engine comprising a revolute cam, cylinders, pistons in the cylinders, said pistons being provided with parts adapted to follow the cam, arms pivotally connected at one end to the pistons, said arms being pivoted to each other between their ends, and yielding means reacting between the opposite ends of the arms for causing the pistons to follow the cam.

12. An engine having a relatively revolute cam and cylinders, pistons in the cylinders, the pistons being provided with parts bearing against the cam, and self-adjusting means connecting the pistons for causing each to at all times resist motion of the other away from the cam, said connecting means comprising oppositely acting levers and an hydraulic cushion interposed between said levers and resisting independent rotation thereof.

13. In an engine a revolute cam, radially arranged cylinders, pistons in the cylinders having portions engaging the cam, means connecting the pistons and adjustable in response to variations in contraction and expansion of the cooperating parts for causing each to at all times resist movement of the other away from the cam, said means comprising levers having a common pivot and means connecting the levers so as to permit conjoint rotation thereof but resisting independent rotation thereof.

In testimony whereof I affix my signature.

CHARLES F. KETTERING.
